DESIGN FOR A COLORIMETER

Stanley J. Bailey, Snyder, and Roger S. Estey,
Buffalo, N. Y., assignors to Spencer Lens Com-
pany, Buffalo, N. Y., a corporation of New York

Application February 14, 1940, Serial No. 90,256

Term of patent 14 years

To all whom it may concern:

Be it known that we, Stanley J. Bailey and Roger S. Estey, citizens of the United States, residing at Snyder and Buffalo, respectively, in the county of Erie and State of New York, have invented a new, original, and ornamental Design for Colorimeters, of which the following is a specification, reference being made to the accompanying drawings forming a part thereof.

Fig. 1 is a perspective view of a colorimeter showing our new design; and

Fig. 2 is a perspective view of the opposite side of the same as disclosed in Fig. 1.

The characteristic features of the design are shown in full lines in the drawings.

We claim:

The ornamental design for a colorimeter, substantially as shown and described.

STANLEY J. BAILEY.
ROGER S. ESTEY.
